UNITED STATES PATENT OFFICE.

CHRISTIAN HELSCHER AND FRANK W. KOONTZ, OF MASSILLION, OHIO.

KEY HOLDER.

Application filed March 29, 1922. Serial No. 547,746.

To all whom it may concern:

Be it known that CHRISTIAN HELSCHER and FRANK W. KOONTZ, citizens of the United States, residing at Massillon, in the county of Stark, State of Ohio, have invented a new and useful Key Holder; and we do hereby declare the following to be a full, clear, and exact description of the invention, such as will enable others skilled in the art to which it appertains to make and use the same.

The invention relates to key holders and has for its object to provide a device of this character which is carried by the key hole plate of a door lock and pivoted thereto and provided with means for engaging and holding a key extending through the key hole against rotation, thereby preventing not only the turning of the key, but at the same time preventing the key from being pushed out of the lock.

A further object is to provide a key holder for door locks, said holder comprising a body member having a transversely disposed member adapted to engage in the key hole and be turned therein for attaching the body member to the key hole plate. Also to provide the body member with a notch for the reception of a rectangular shaped portion of a key shank and a hooked member pivoted to the body member for holding the shank of the key in the notch of the body member.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawing:—

Figure 1 is a front elevation of a conventional form of key hole plate, showing a key therein and the key holding device applied thereto.

Figure 2 is a side elevation of a portion of a key hole plate showing the device applied thereto.

Figure 3 is a plan view of a key having a rectangular shaped shank and adapted to be held by the key holding device.

Figure 4 is a top plan view of the key.

Referring to the drawing, the numeral 1

designates a conventional form of key hole plate used in connection with door locks and 2 a key hole therein. Pivots connected at 3 adjacent the key hole 2 is a plate 4, which plate when moved to vertical position shown 60 in Figure 1, covers the key hole 2. The plate 4 adjacent its upper end is provided with a recess 5, which recess receives the rectangular shaped portion 6 of the key 7 in such a manner as to hold the key against 65 rotation. The rectangular shaped portion 6 is reduced in relation to the shank 8 of the key thereby forming shoulders 9 which will prevent the key from being forced out of the key hole 2 and consequently prevent- 70 ing opening of the lock by means of a skeleton key. To prevent the plate 4 from moving out of operative position as shown in Figure 1, a hook 10 is provided, which hook is pivotally connected at 11 to the plate 4 75 and hooks over the rectangular shaped portion 6 of the key shank 8, thereby preventing displacement of the same and maintaining the plate in locked position as shown in Figure 1. It will be noted that the key can- 80 not be turned in the lock for the reason that the rectangular shaped portion 6 of the key will engage the upper and lower walls 5^a of the recess 5.

Referring to Figure 3 wherein a modified 85 form is shown, the construction is substantially the same as in Figures 1 and 2 with the exception that the plate 4 is provided with a plate 12 having a reduced shank 13. The plate 12 when moved to a vertical position in the key hole below the key 7 and the device as a whole to vertical position, forms means for securing the device to the key hole plate 1 in such a manner that its shoulders 14 will engage the inner side of 90 the plate 1 and prevent displacement of the device. The form shown in figure 3 is of a portable type and may be attached to key hole plates in hotels and the like and is 95 particularly adapted.

From the above it will be seen that a key holder is provided, which is simple in construction, the parts reduced to a minimum and one which may be easily and quickly applied to a key hole plate.

The invention having been set forth what is claimed as new and useful is:—

The combination with a key hole plate having a key hole therein, of means for preventing rotation and removal of a key,

100

105

110

said means comprising a plate, a shouldered member carried by one end of the plate and adapted to pass into the key hole and be turned to a position where the shoulders thereof will prevent removal of the plate, a hooked member pivotally connected to the free end of the plate and adjacent a recess in the plate, said hooked member forming means for hooking over the shank of the key and holding the same in the recess, said shank of the key being rectangular shaped

and of sufficient size to prevent rotation thereof in the recess.

In testimony whereof we have signed our names to this specification in the presence 15 of two subscribing witnesses.

CHRISTIAN HELSCHER.
FRANK W. KOONTZ.
